UNITED STATES PATENT OFFICE.

WILLIAM B. POTTER, OF SCHENECTADY, NEW YORK, ASSIGNOR TO GENERAL ELECTRIC COMPANY, A CORPORATION OF NEW YORK.

SOUND-REPRODUCING DEVICE.

Application filed October 21, 1924. Serial No. 745,015.

To all whom it may concern:

Be it known that I, WILLIAM B. POTTER, a citizen of the United States, residing at Schenectady, in the county of Schenectady, 5 State of New York, have invented certain new and useful Improvements in Sound-Reproducing Devices, of which the following is a specification.

My present invention relates to sound 10 reproducing devices of the type commonly known in the art of radio reception as loud speakers.

The object of my invention is to provide an efficient form of device which will faithfully 15 reproduce in large volume sounds such as music or speech without at the same time producing distortion by reason of resonant effects of vibrating apparatus or resonant air columns.

20 The novel features which I believe to be characteristic of my invention are set forth with particularity in the appended claims. My invention itself, however, both as to its organization and method of operation will 25 best be understood by reference to the following description taken in connection with the accompanying drawing in which Fig. 1 is a front elevation of a device embodying my invention; Fig. 2 is a side elevation with 30 a portion broken away; Fig. 3 is a detail cross section showing the method of driving a diaphragm constructed in accordance with my invention; Fig. 4 is a partial cross-sectional view of the diaphragm; and Fig. 5 35 is a detail illustrating a method of supporting the diaphragm.

I have indicated in the drawing a diaphragm which comprises a cone 1 of light material such as stiff paper. The edge of 40 the base of the cone 1 is bent outwardly to form a flange 2. The cone is reinforced or made rigid in order that it may be capable of vibrating substantially as a whole by means of the frustum 3 of another cone of 45 the same diameter. The edge of the base of the frustum 3 is bent outwardly to form a flange 4, which may be secured to the flange 2 by any suitable adhesive. The frustum 3 is open at its top and the upper edge may 50 be bent outwardly at 5 and reinforced by means of a reinforcing band 6 to add rigidity to the structure.

The diaphragm as described is flexibly supported from the periphery of the base of 55 the cone 1 by means of cords 7 passing

through and tied to eyelets 8 formed in the base flange. The cords 7 may be threaded through holes 9 in a supporting ring 10 and wound around the screws 11. The cords 7 may be drawn up to a desired tension and 60 secured by tightening the screws 11. The supporting ring 10 may be formed of a strip of metal having its ends secured together by a bolt 12. The ends of the strip may also be bent into a common plane and 65 secured to a supporting base 13 by means of screws 14.

The diaphragm thus constructed and supported may be actuated by any desired form of driver. I have indicated in Fig. 3 in a 70 more or less diagrammatic manner one way in which the diaphragm may be actuated. I have shown an actuating means comprising in its essential aspects a common form of telephone receiver having a vibrating diaphragm 14 in proximity to pole pieces 15 of a magnet which are surrounded by coils 16 to which actuating currents may be supplied. A rod 17 is secured to the diaphragm 14 by 75 means of a screw 18. The apex of the cone 1 is preferably reinforced by means of reinforcing members 19 and rod 17 is secured to the apex of the cone by means of a screw 20. The actuating means may be secured by a clamping member 21 to a standard 22, 80 which in turn is supported by the base 13.

I have found that a diaphragm constructed and supported as described may be made to reproduce with great accuracy any desired sounds. Because of the flexible support 85 the diaphragm is under little restraint and tends to vibrate as a whole. Resonant effects common to diaphragms which are under restraint are largely eliminated.

By making the area on top of the frustum 3 materially less than the area of the base of the cone 1, the sounds produced in the interior of the cone 1 are propagated more or less in beam fashion instead of being transmitted through a wide area. At 95 the same time the sounds produced are not confined in any place to such a restricted cross sectional area that there is any resonant air effect introduced such as is common with many horns employed with loud speakers. The sharpness of this directive effect will of course depend to a large extent 100 upon the area of the top of the frustum 3.

By locating the driving means outside of 105 the cone also there is no obstruction to the 110

free propagation of sounds from the entire inner area of the cone.

While I have shown and described only one embodiment of my invention it will be apparent that many modifications in the manner of carrying it out may be made without departing from the scope thereof as set forth in the appended claims.

What I claim as new and desire to secure by Letters Patent of the United States is:—

1. Sound reproducing means comprising a diaphragm having the form of a hollow cone made rigid by the frustum of a cone secured to its base, said cone being flexibly supported from the periphery of its base, and actuating means for said diaphragm located outside said cone and secured to said cone at its apex.
2. Sound reproducing means comprising a diaphragm having the form of a hollow cone having a frustum of another cone joined thereto at its base, the top of said frustum being open and the upper edge thereof being bent outwardly, said cone being flexibly supported from the periphery of its base, and actuating means for said diaphragm located outside said cone and secured thereto at its apex.
3. Sound reproducing means comprising a diaphragm having the form of a hollow cone having a frustum of another cone joined thereto at its base, the top of said frustum being open and the upper edge

thereof being bent outwardly and reinforced by a stiffening band, said cone being flexibly supported from the periphery of its base, and actuating means for said diaphragm located outside said cone and secured thereto at its apex.

4. Sound reproducing means comprising a diaphragm having the form of a hollow cone, made rigid by the frustum of a cone secured to its base, said cone being flexibly supported from the periphery of its base, and actuating means for said diaphragm located outside said cone and secured to said cone at its apex, the top of said frustum being open and having an area materially less than the area of its base whereby the sound produced at the inner surface of said cone is propagated in beam fashion.

5. Sound reproducing means comprising a diaphragm having the form of a hollow cone, a second hollow member having two open ends, one of which is joined to the base of said cone to render it more rigid, means for flexibly supporting said cone from the periphery of its base, and actuating means for said diaphragm located outside said cone and secured thereto at its apex, said second hollow member being adapted to direct the sound produced at the inner surface of said cone.

In witness whereof, I have hereunto set my hand this 20th day of October, 1924.

WILLIAM B. POTTER.
